(57) **CLAIM**

The ornamental design for a wireless charging holder, as shown and described.

DESCRIPTION

FIG. 1 is a front perspective view of a wireless charging holder, shown in a first configuration;

FIG. 2 is a rear perspective view thereof;

FIG. 3 is a bottom perspective view thereof;

FIG. 4 is a front view thereof;

FIG. 5 is a rear view thereof;

FIG. 6 is a left side view thereof;

FIG. 7 is a right side view thereof;

FIG. 8 is a top view thereof;

FIG. 9 is a bottom view thereof;

FIG. 10 is a front perspective view of the wireless charging holder, shown in a second configuration with a bigger circular plate inclined upward;

FIG. 11 is a rear perspective view thereof; and,

FIG. 12 is a rear perspective view of the wireless charging holder, shown in a third configuration with the supporting post folded.

The broken lines in the drawings depict portions of the wireless charging holder that form no part of the claimed design.

1 Claim, 12 Drawing Sheets
